4 Claims. (Cl. 86—48)

This invention concerns improvements in or relating to machines for inserting cartridges into belts to form belts for automatic guns and refers more particularly to a machine for inserting cartridges into belts made of fabric or other flexible material, and provided with loops or pockets evenly spaced apart, for receiving cartridges. Various forms of such belts are known and usually they consist of two pieces of webbing or like material which are joined together to form a double thickness by sewing or weaving, the seams being so disposed that small flat loops or pockets are formed at regular intervals along the length of the belt into which the cartridges are inserted. Some belts (hereinafter called "the first type of belt") have the seams extending to the extreme edges or selvedges of the belt, while in other cases (hereinafter called "the second type of belt") the seams terminate a short distance (e. g. $\frac{1}{8}$ of an inch) from the edges on that side from which cartridges are to be inserted and referred to as the "entry edges." Generally the major portion of each loop or pocket is of a width suitable to engage the main body part of the brass shell or case of the cartridge, while the remaining portion of the pocket is narrower and of such size as to receive the stepped down diameter of the case which holds the projectile in position. All such belts will be termed herein "belts of the kind described."

According to the invention, there is provided a machine for inserting cartridges into belts of the kind described, having means for intermittently feeding the belt and means for moving a cartridge transversely of the belt and inserting it into a pocket or loop thereof, comprising means for turning a cartridge being fed towards the entry edge of the belt askew so that the nose of the bullet of said cartridge is directed towards that end of the corresponding loop which is the rear end, considered in the direction in which the belt is being fed, and means for locating such end of the loop relatively to the nose of the bullet to facilitate the insertion of the cartridge. The locating means for the end of the pocket or loop may comprise means which engage the material of the belt on each side of said pocket or loop to hold it taut. The means to hold the material of the belt on each side of the pocket or loop may be adapted to provide a relative movement between the sides of the pocket or loop so that they move towards one another after the nose of the bullet has opened the rear corner of said loop, whereby the loop is completely opened as the cartridge is completely inserted. The means to

hold the material on each side of the pocket or loop and adapted to provide relative movement between the sides of the pocket, as specified above, is not new in itself, but is claimed herein in combination with a particular way of inserting the cartridge, whereby the two features together cooperate to provide an improved result.

Further according to the present invention there is provided a machine for inserting cartridges in the "second type of belt" wherein there is provided an opening device adapted to separate the entry edges of the belt as the latter is fed along to facilitate the insertion of a cartridge.

An electric contact device may be adapted to cooperate with a metal component in a belt (e. g. a tag or eyelet) to operate a switch to stop the current supply to an electric driving motor and cause the machine to stop when a belt is filled.

One way of carrying the invention into effect will be described with reference to the accompanying drawings which show a machine for inserting rimless cartridges (e. g. .300 of an inch S. A. A.) into a belt of the kind described.

In the drawings:

Figure 1 is a front elevation of the cartridge inserting machine.

Figure 2 is a plan of the cartridge inserting machine.

Figures 3 and 4 are end elevations of Figure 1, the views being taken in the direction of the arrows A and B respectively.

Figure 5 is a sectional view of a fragment of Figure 1 showing more clearly the devices which operate on the cartridges and the belt.

Figure 6 is a view of a fragment of Figure 2 showing more clearly the devices which operate on the cartridges and the belt. In this view a hinged part is swung out of the operative position to show hidden parts more clearly.

Figure 6A shows another view of two parts shown in Figure 6.

Figure 7 is a view of part of a cartridge feeding apparatus and shows how the cartridges are fed to the inserting machine.

Figure 8 shows a portion of the second type of belt.

Figure 9 shows a portion of the first type of belt.

Figure 10 is an isometric diagram of the method of inserting cartridges.

Referring to the drawings, cartridges are fed in any desired manner from any suitable hopper or hoppers to the flutes of a drum 5, which is rotated in timed relationship with a plunger 52 described below, so that a new cartridge is deliv-

ered by the drum 5 after each actuation of the plunger 52, so that a magazine 29 has approximately the same number of superposed cartridges C during operation (see Figure 7).

The machine, including the fluted drum 5, is driven from a mainshaft 14 which carries a pulley driven by a motor or the like or by a hand wheel (not shown) for setting and like operations.

Referring now to Figure 7, the drum 5 is provided with guides or shrouds 28 which retain the cartridges in the flutes until a flute arrives at the lowest position where the cartridges fall into a short vertical magazine 29 in which they form a vertical superimposed column. A stripper 30 ensures that each cartridge falls out of a flute at the proper time. The lowest cartridge in the magazine 29 is ejected axially therefrom by a reciprocating pusher as described later.

As the ejection of the lowest cartridge is liable to cause a disturbance of the remaining superimposed cartridges, in view of their tapering shape a device is provided to support them during the ejecting movement. This device is shown in Figures 1, 2, 3 and 7 and comprises a bevelled plate or wedge 31 attached by means of a flat spring 32 to a bar 33. The bar is fixed to a cam lever 34 having a roller 35 thereon which engages a cam 36. The cam is fixed on a camshaft 64 described later and a spring 37 effects the return movement. The spring 32 gives the plate 31 sufficient flexibility to enable it to enter between the lowest cartridge in the magazine and the one above it in spite of small variations in the disposition of the cartridges in the magazine due to their tapering shape. As shown in Figure 7, the plate 31 is about to move between the two cartridges when it will lift slightly as it rides over the lowest one and raise the other four in the magazine slightly above the position shown and also cause the lowest round to move to the left in Figure 7 against the left-handed side of the magazine 29 so that the axis of said round is slightly askew (see also Figure 2).

The table 50 of the cartridge inserting machine is horizontally disposed and supported on a bed 51. In alignment with the lowest cartridge in the magazine 29 there is provided a reciprocating pusher 52 which engages each cartridge in turn and pushes it into a loop of a belt. The pusher is adjustably supported on a slide 53 mounted in a horizontal guide 54 fixed to the bed and is reciprocated by means of a lever 55 which is pivoted at 56 to a bracket 57 fixed to the base of the bed of the machine. The upper end of the lever is connected at 58 to a link 59 pivoted at 60 to the pusher slide. The lever 55 is oscillated by an eccentric rod 61 which is driven by an eccentric 62 carried on the mainshaft 14. A camshaft 64 is rotatably mounted in bearings formed in the bed and is geared to the shaft 14 by bevel gear wheels 65 and 66.

The cartridge belt C. B. is fed across the table 50 and through the machine transversely to the direction of movement of the cartridge pusher 52, by means of a lever 68 provided with a cartridge engaging member 69 at one end, having pairs of semi-circular grooves 70, each pair being adapted to engage a cartridge. The cartridge engaging member projects upwardly through slots 71 in the table of the machine, and engages a cartridge in the belt, the reaction being taken by a top plate or guide 72 normally fixed at a suitable distance above the table of the machine. When the member 69 has engaged the cartridge 75

in this manner, the member is moved horizontally for a distance equal to the pitch of the cartridges in the finished belt, whereafter the member is moved out of engagement with said cartridge, and moves down clear of the belt on its return stroke, at the end of which it moves up towards the belt again and engages the next cartridge. As shown, the cartridge feeding member 69 is fixed at one end of the lever 68 and the other end of this lever is pivoted at 73 to a cam lever 74. This cam lever is pivoted at its lower end on a shaft 75 fixed in the bed 51 and is oscillated about said pivot by means of a roller 76 on the lever which engages a cam 77 fixed on the camshaft 64 previously mentioned. The cam is arranged to positively move the cartridge feeding member on the belt feeding stroke, and the return stroke is effected by a spring 78. The lever 68 which carries the cartridge engaging member is provided with a roller 79 which engages another cam 80 on the camshaft and during the return movement of the cartridge-engaging member, this second cam moves the lever about its pivot and permits the cartridge engaging member to move away from the cartridge belt under the action of a spring 102.

When the belt is first placed into the machine, a cartridge is inserted by hand into the first belt pocket at the leading end of the belt, and this cartridge is so disposed that it is engaged by the first pair of grooves 70 (i. e. the left hand pair Figure 6) of the cartridge engaging member 69, so that when the machine is turned, positive feeding of the belt immediately takes place. When the belt is located in this manner, a pair of gripping devices, comprising plates 81 and 82 having narrow edges, are moved into engagement with the cartridge belt at a position located between the cartridge inserted into the belt in the manner described, and the following empty loop or pocket. The edges of the gripper plates are serrated, see Figure 3.

A gripping device is fixed to one end of each of two double armed levers 83 and 84, said levers being pivoted at 85 and 86 respectively on brackets 87 and 88 fixed beneath the table and on the upper surface of the top plate 72 respectively. Compression springs 89 are fitted to the levers at positions between the gripping devices and the pivot points, and levers 90 and 91 are attached to the pivot pins, the free ends of the levers being bent inwards towards one another at 103 in such manner that they can be simultaneously engaged by a roller 104 mounted on the upper end of an oscillating lever 92. As the end of said lever moves away from the pivot points of the gripper levers, the roller engages the inwardly bent ends of the gripper operating levers and thus causes the two grippers to approach one another and grip the material of the belt. As the lever carrying the roller moves in the opposite direction the grippers are opened by the action of the compression springs, the extent of the movement being controlled by abutments or stops 105 formed on the gripper levers and which engage with surfaces of the table and top plate respectively. The lever 92 which operates the grippers is pivoted on the shaft 75 and is provided with a roller 93 engaging another cam 94 fixed on the camshaft 64.

When the grippers have moved into operative engagement with the material of the belt, the cartridge pusher 52 operates and presses the lowest cartridge in the magazine 29 forwardly so that its nose tends to enter the second loop

in the belt. In a belt as manufactured, the loops are quite flat and the insertion of a cartridge into such a loop is a comparatively difficult and uncertain operation. Means are therefore provided to assist the loop to open as the nose of a cartridge is presented thereto. While the material of the belt is gripped by the grippers previously described at a position between the cartridge already in the belt and the next empty loop, the belt is engaged by a feeder 95 at a position just beyond the other side of the said loop. The feeder comprises a lever pivoted at 96 to one arm 97 of a double armed cam lever and having its free end serrated or roughened on the face 98 which engages the belt.

The feeder is caused to move to the right, Figure 1, by a roller 99 on the other arm 100 of the cam lever which engages a further cam 106 on the camshaft 64, the return movement being by the spring 102 previously mentioned. The feeder is pressed into operative engagement with the belt by a roller 107 pivoted on an arm 108 extending from the lower gripper 81 so that as the gripper moves upwards the feeder is pressed on to the belt and at this time is moving to the right Figure 1. As the grippers separate, the feeder falls away and is checked by a stop 109 and at this time is moving back on its return stroke.

The upper side of the belt is supported by an abutment 101 on the top plate 72 to provide the necessary reaction to the feeder pressure. The serrations on the feeder are preferably formed by sharp edged grooves or points formed therein parallel to the direction of movement of the belt.

As the feeder moves forwardly, that is towards the cartridge already inserted by hand into the first pocket of the belt, the material comprising the loop, which as aforesaid is gripped at one side by the grippers, is thus gathered and the loop tends to open.

Two kinds of belts are shown in Figures 8 and 9. The belts consist of two separate plies of fabric joined together by threads interwoven or sewn and represented in the figures by thick dash lines.

The belt shown in Figure 8 is of the "second kind" and the two strips or webs of material which form the belt are not joined at the extreme lower edge as the dashes do not extend to the edge. This is the edge referred to hereinafter as the entry edge at which the insertion of cartridges takes place. In this case a device is provided for opening the two entry edges to facilitate the insertion of cartridges. The device comprises a knife-like member 110 fixed to the table and adapted to separate the edges as the belt feeds along. It is located near the feeder 95 as shown in Figure 6 and its shape may be followed by reference also to Figure 6A. To control the belt as it moves towards the gripping, feeding and opening devices, guides 111 are provided and in order to bring the entry edges of the belt substantially into alignment with the nose of a bullet, a packing plate 112 is fixed between said guides. As the belt leaves the guides it is received on a locating plate 113, see also Figure 6A, and as it passes from the inserting position it is controlled by guides 114. Sloping guides or ribs 115 are fixed to the table 50 and to the top plate 72 to engage the bullets and assist in guiding the belt.

The method of inserting the cartridges is shown in Figure 10 and Figures 2 and 7 should also be considered when studying the method. In order to facilitate the entry of a cartridge into

5 a loop which at this stage is held taut by the grippers as shown in the drawings, guides are provided which turn the cartridge askew. As will be seen from Figure 7, the magazine 29 is formed by two brackets 129 and 130 which are fixed to the table 50. The brackets have inner guide faces 290, 291, 300, and 301 to fit the tapering shape of the cartridges, but the guide 290 is cut away at the bottom. See Figure 7.

10 Thus as the wedge 31 moves inwardly as described above, it will cause the lowermost cartridge to line up against the guide face 291 and the cut away portion of the guide 290 so that it lies against the part 129 slightly askew and on 15 actuation of the plunger 52 will advance in this line since the wedge 31, see Figures 2 and 7, will tend to keep it askew.

Only after the round has entered the belt and is caused thereby to straighten up, is there 20 enough resistance to cause the round to overcome the pushing action of the wedge 31 to cause the latter to rise and raise the cartridges above it. Thus the lowest cartridge in the magazine is caused, by the pressure of those above it, and 25 by the pressure of the wedge 31, to turn its nose to the left in the manner shown in Figure 10. In Figure 10, the axes of the cartridge being inserted and of the pusher 52 are shown by chain lines and show the cartridge entering the loop while 30 it is still taut. The axes lie in the same horizontal plane but at an angle to each other. The effect is to cause the nose of the cartridge to move very near towards one end, (i. e. where the seam which defines a loop is formed in the belt), of the still flat loop. The loop end in question is the one adjoining the feeder and its horizontal disposition is located very accurately by the feeder 95 and the abutment 101.

35 Thus as a cartridge is pressed by the pusher 40 52 its nose will open the corner of the pocket. This operation is followed immediately by the gathering referred to above.

45 Simultaneously the nose of the first cartridge fed by the pusher 52 is pressed into the loop and the combined operation causes the loop to open completely and certainly and the cartridge is pushed home by the pusher. The feeder then moves back. Once the entry has been effected, the cartridge can slew around into its true position, in alignment with the pusher and at right angles to the length of the belt.

50 In the construction shown, a contact bar 120 is provided which is connected to the switch circuit in such manner that if a connection occurs between the bar 120 and the machine frame, the motor will stop. The bar is fixed on an insulating block 121 which is in turn fixed to a lever 122 pivoted on the spindle 116 which is also supported by a bracket 123 fixed on the table. The bar may be raised for inserting a belt and held in the inoperative position by a stepped portion 124 on the boss of the lever 122 which engages a stepped collar 125 under the pressure of a torsion spring 126. The belt is provided with metal eyelets 127, 55 Figure 10, at each end and as the rear eyelet passes beneath the bar contact is made to the table 50 and the motor is stopped.

60 The time of contact is so chosen, by experiment, that the inertia of the moving parts of the machine is sufficient just to complete the filling of the belt and no more.

65 Figure 9 shows "the first kind of belt" and the principal difference in this kind of belt over that shown in Figure 8 is that the sewing or interweaving which joins the two plies of material and de-

fines the pockets or loops extends to the extreme or entry edges so that it is not possible to use the knife 110 to effect the preliminary opening of the loops. It will also be noticed that a long metal tag 128 is used in place of the eyelet 127 but this is not material as the electric contact bar 120 can be shifted to secure the proper timing.

What we claim as our invention and desire to secure by Letters Patent is:

1. A machine for inserting cartridges into fabric-type belts provided with loops for receiving the cartridges, comprising means for intermittently feeding the belt in the direction of its length, means for moving cartridges transversely of the belt and inserting a cartridge into a loop, 10 means for turning a cartridge being fed towards the belt obliquely with respect to the length of the belt so that the nose of the bullet of said cartridge is directed towards that end of the corresponding loop which is the rear end, considered in the direction in which the belt is being fed, and means for locating such end of the loop relatively to the nose of the bullet to facilitate the insertion of the cartridge.

2. A machine as claimed in claim 1 wherein said locating means comprises means to engage the belt on each side of a loop to hold the belt taut.

3. A machine as claimed in claim 1 wherein the said locating means engages the belt on each side of a loop to hold the belt on each side of a loop to hold the belt taut and is movable to cause relative movement between the sides of the loop to cause the latter to approach one another after the nose of the bullet has entered the corner of the loop whereby the loop is completely opened as the cartridge is completely inserted.

4. A machine as claimed in claim 1 comprising an electric contact device adapted to co-operate with a metal component in a belt to operate a switch to stop the current supply to an electric driving motor and cause the machine to stop when a belt is filled.

CHARLES THOMAS HALL,
RICHARD WILLIAM HARRIS.
